UNITED STATES PATENT OFFICE

2,431,606

TOOTHBRUSH

George L. Briggs, Oneida, N. Y.

Application June 11, 1946, Serial No. 675,953

1 Claim. (Cl. 15—106)

1

This invention relates to an improved toothbrush, useful where it is desired to suspend the brush vertically in a rack without deformation of the tufts of bristles.

The usual form of rack in which toothbrushes are placed after use is provided with a plurality of vertical slots of shape and size to admit the handle of the brush and refuse admission to the bristles. As a result, the brush is supported by the tufts of bristles which engage the upper surface of the rack and in a short time these tufts become deformed by the weight of the brush, with consequent impairment of the usefulness and appearance of the toothbrush. I am aware that various forms of brush handles have been proposed, where the handle is provided with a protuberance in the region adjacent to, or even remote from, the bristles. While these protuberances serve to keep the working part of the toothbrush from contact with the rack, they all have the disadvantage of interfering with the operation of brushing the teeth.

In my improved toothbrush, instead of an unyielding bulge at or below the junction of the head with the handle of the brush, I provide an additional tuft of bristles, isolated from the working tufts and secured to the handle a convenient distance below the head. Such an additional tuft engages the upper surface of the receptacle in which the brush is racked and thereby supports the brush without in any way interfering with brushing the teeth of the user.

The object of the invention, therefore, is to provide a toothbrush adapted to be used without discomfort and to be supported vertically in a rack without deformation of the working bristles.

The invention will be understood from the following description, read with reference to the accompanying drawing, in which:

Figure 1 is a perspective view of the improved toothbrush of the invention, and

Figure 2 is a side view of the brush of Figure 1 supported in a rack of usual form.

In both figures, like numerals identify like parts.

Referring now to Figure 1, in head 10 of the toothbrush indicated generally by the numeral 5 are secured the usual tufts of bristles 11. Forming a continuation of head 10 is handle 12, which may have a laterally narrowed portion 13 in the region below bristles 11. Such lateral narrowing

2

of the handle, while commonly provided, is in no way needed when the brush is to be racked in a receptacle vertically slotted to admit the handle.

Additional to tufts 11, I provide an isolated tuft 5 of bristles 14 secured in the handle at a convenient distance below the lowest array of tufts 11 and on the same side of the handle as those tufts. The office of tuft 14 is clearly shown in Figure 2, where brush 5 is shown supported in rack 15, of conventional design provided with one or more vertical slots such as slot 16. For simplicity, rack 15 is shown in vertical section through the portion surrounding slot 16.

As plainly evident from Figure 2, tuft 14 engages the upper surface of rack 15 and supports the toothbrush with tufts 11 clear of the rack surface. Thereby at least two advantages are afforded by the invention; tufts 11 are protected from becoming misshapen from bearing the 10 weight of the brush, and contamination of the surface of rack 15 by a residue of toothpaste on tufts 11 is largely prevented. Moreover, tuft 14 being like one of the working tufts 11, it may enter the mouth of the user without causing discomfort or interfering with brushing the teeth. 20 It will be understood that while one additional tuft 14 will accomplish the object of the invention, two or more such tufts side by side may be provided if desired.

30 I claim:

A toothbrush adapted to be vertically supported in a rack provided with an aperture to receive the brush comprising a head, a plurality of tufts of bristles secured in the head, a handle forming a 35 continuation of the head beyond the tufts, and an additional tuft of bristles secured in the handle near the junction thereof with the head, the additional tuft serving to support the brush by engaging the upper surface of the rack.

GEORGE L. BRIGGS.
